COLLATING MACHINE

Luis Mestre, 305 E. 46th St., New York, N.Y.

Filed Nov. 26, 1957, Ser. No. 698,992

47 Claims. (Cl. 270—58)

The invention relates to a collating machine which withdraws the top sheet or page from a plurality of like sheets in each of a series of storage pockets and assembles them together in sequence at a deposit point or platform so that they may be secured or stapled together. The collating machine described herein preferably uses a rotary storage drum with generally radial storage pockets. If a booklet for example comprises eight pages, a page is withdrawn from each of eight storage pockets of the drum and deposited in one relative position. The next eight pages are then deposited in another relative position with respect to the first so that each set of sheets of eight pages are easily separated from each other.

In a collating machine it is desirable that the machine have considerable flexibility so that the machine may be set up for a book or booklet of few or more sheets up to the capacity of the storage means or drum. Or the machine may be loaded with sheets to be assembled into different books or booklets for example, one book may comprise eight pages, a second book six pages, a third book four pages and so forth and the machine sorts the pages of each book into a separate and proper set and in proper page sequence. Again a booklet may have eight pages, and another booklet may have the same eight pages and one, two, or more additional sheets. The machine also will collate automatically such similar books. Many other variations of collating may be accomplished with the machine.

It is an object of the invention to construct a collating machine having a new and novel mechanism for securing relative separation or spacing between groups of sheets.

Another object is to construct a collating machine which automatically stops if a plurality of sheets are carried by the clamping means.

A still further object is to provide a collating machine which automatically stops when a sheet is missing in a clamping means which should have a sheet.

Another object is to render inoperative the above automatic stop for any clamping means which is intentionally not carrying a sheet.

Another object is to construct a collating machine utilizing means for opening the clamping means at different positions to effect separation of alternate groups of a plurality of sheets.

A still further object is to provide a collating machine with a new and effective mechanism for assembling a series of sheets on a depositing platform in groups of one or more sheets alternately at two different inline and overlying positions so that each group may be separated.

Another object is to construct a collating machine with clamping means which are held away from contact with the pile of sheets in a pocket when the clamp is closed.

Another object is to provide a collating machine having clamping means which are held in raised position after withdrawing a sheet from the pocket and clamping the sheet.

A still further object is to have a clamping means which

2

can be selectively closed so that it will not pick up a sheet and when closed is held away from contact with the sheets in its cooperating storage pocket.

Other objects will be more apparent from the following description when taken in connection with the accompanying drawings illustrating a preferred embodiment of the invention in which:

Fig. 1 is an elevation of the principal parts of the collating machine taken from the rear of the machine;

Fig. 2 is a front elevation of the collating machine;

Fig. 3 is an enlarged detailed view of the mechanism for shifting the clamping means from extending in one direction to a position where they extend in the other direction as well as illustrating the clamping means picking up a sheet from a pocket of the storage means;

Fig. 4 is a detailed enlarged view of the means for opening the clamping means in two positions to release a sheet at different times;

Fig. 5 is a view similar to Fig. 4 in which the clamping means is opened at a later time;

Fig. 6 is a top view of the clamping means;

Fig. 7 is a side elevation of the clamping means in closed position;

Fig. 8 is a plan view of the clamping means taken on line 8—8 of Fig. 6;

Fig. 9 is a section of the clamping means taken on line 9—9 of Fig. 6;

Fig. 10 is a view of the opening lever for the clamping means taken on line 10—10 of Fig. 6;

Fig. 11 is an end view of the collating machine at the depositing end thereof;

Fig. 12 is a detailed view of the cam which operates the sheet gaging means and the missing sheet means;

Fig. 13 is a front view of the contacts for stopping the machine for a plurality of sheets or no sheet in a clamping means;

Fig. 14 is an end view of the clamping means;

Fig. 21 is another view of the clamping means taken on line 21—21 of Fig. 17;

Fig. 22 is a partial view of the clamping means as it picks up a sheet from a pocket of the storage means;

Fig. 23 is a view similar to the view of Fig. 22 but shows the mechanism for holding the clamping means out of contact with a sheet in a pocket of the storage means when the clamping means is closed;

Fig. 24 is a diagrammatic circuit for the detector means and its throwout switch, the gaging circuit and its throw-out switch;

Fig. 25 is a general view of the scroll at the gaging means and detector means showing the directing of a sheet to the means and the separation of the preceding sheet therefrom.

The collating machine as to its general aspects provides a main frame 26 of many parts for supporting all of the mechanism. The machine includes a storage means having a plurality of pockets for sheets shown particularly as a rotating circular drum 27 with radial pockets therein open at the periphery for holding the various sheets which

are to be assembled as a book or booklet. Each pocket is adapted to carry a quantity of sheets of one kind or sheet number. With the circular storage means illustrated the drum rotates continuously. The machine also includes a plurality of continuously moving clamping mechanisms each of which includes a clamping means which removes one sheet from its pocket at pickup position and delivers the sheet to an assembling or depositing platform of any suitable type. Each clamping mechanism withdraws a sheet from its pocket, clamps the sheet for transport to the depositing platform or depositing position and returns to pickup position at the storage means. Groups of sheets are deposited on the depositing platform in alternately staggered relation for easy separation of each group. The machine particularly shows a depositing platform which is fed downwardly as the sheets or pages are deposited thereon. Finally the machine includes electrical control means for controlling the desired operation of the machine.

Storage means

The storage means which is adapted to hold the sheets to be collated includes a series of pockets which move successively to pick-up position. The storage means preferably is a circular drum 27 mounted on a shaft 28. The drum is rotated by a motor 29 connected with a reduction gear unit 30 and a suitable connection is made from this gear unit to the shaft of the drum to rotate it at a uniform speed. The driving connection shown includes a chain 31 and sprocket 32 on the drum shaft 28.

The drum carries generally radial pockets formed by partitions 36 extending in a general radial direction. Preferably the partitions project not towards the center of the drum but project tangent to the bottom of a circle having the center of the drum as the center so that in the upper right hand quadrant of the drum, as shown in Fig. 2 where the sheet pick-up position is located, the partitions and sheets are in an inclined or angular position. The drum has spaced side plates 37 to which the partitions are secured in any desired manner and at least one side plate carries a slot 38 for each pocket. A pocket bottom rest 39, Fig. 1, is mounted in each slot 31 so that the depth of each pocket may be adjusted as desired for the length of the sheets S to be stored therein. Any suitable bottom rest may be used.

For a rotating drum storage means, means are provided to hold or clamp the plurality of sheets in each pocket through substantially three fourths of the revolution of the drum and to unclamp the same at pick-up position of the pockets where a sheet is withdrawn from the pockets. This pocket clamping means (Fig. 1) comprises a pair of pocket clamping plates 41 and 42 each mounted upon a pivotal shaft 43 mounted in the side plates of the drum. The shafts 43 are spaced from each other. One plate 41 extends angularly outwardly towards the periphery of the drum and the other plate 42 extends angularly inwardly. A lever 44 is attached to each pivotal shaft and a spring or springs 45 connected between the levers for each pair of clamping plates propel the plates with their ends into clamping contact with the package of sheets in its pocket to hold the sheets against a partition. Each lever carries a cam roller or follower 46 at its end for engagement with an opening cam 47 which comprises a radial band having a pointed lower end 48 and providing camming surfaces or edges. One roller engages the inner camming surface to swing the inner clamping plates to open or unclamped position and the roller for the other clamping plate engages the upper or outer surface of the radial cam and propels its clamping plates 41 to open position thereby releasing both clamping plates from contact with the package of sheets in its pocket. These pocket clamps are held in unclamped position for approximately 90° of the revolution of the drum by the radial cam through the sheet pick-up position. The radial cam is mounted on the main frame 26. When the rollers ride off of the

end of the radial cam at the top of the machine, the springs 45 pull the cam plates to sheet clamping position.

Transporting mechanism

A plurality of spaced clamping mechanisms are provided, each of which picks up or grips the top sheet in its respective pocket of the storage means or drum and transports the sheet to a depositing position or platform. There is one clamping mechanism for each pocket of the storage means. Each clamping mechanism includes a clamping means or gripper mounted on an endless means of any suitable kind. The endless means shown comprises a pair of spaced chains 52 (Figs. 1 and 11) each of which is carried on a series of spaced sprockets or wheels 53, 54, 55, three being particularly shown for each chain mounted on shafts 56, 57, 58 respectively. The shafts are rotatably mounted on the main frame 26. Two pairs of sprocket wheels 53, 54 are provided adjacent the periphery of the storage means or drum and are spaced with respect to the path of movement of the pockets or the periphery of the drum so that the clamping means contacts the top sheet in a pocket and gradually moves away from the pocket or periphery of the drum and in so moving slides the top sheet therewith until its edge is far enough out for the clamping means to grip the sheet whereupon it is transported to the depositing platform. The span of each chain between the sprocket wheels may be supported by spaced chain guides 59 carried by the main frame and between which the chain travels.

Clamping mechanism

Each chain carries for its entire length a plurality of spaced brackets 63 (Figs. 6-9) each secured to a link thereof so as not to interfere with bending of the chain and projecting in an outward direction. A bearing 64 is provided in each bracket and receives a clamping mechanism. Each clamping mechanism has a clamping means frame including a mounting bar 65 having its end pivotally mounted in a pair of spaced chain brackets, one carried by each of the chains. The clamping means frame includes spaced extensions 66 on each bar.

The clamping means includes a shaft 73 pivotally mounted in the spaced extensions 66. A pair of spaced clamping arms 74 are secured to the shaft so that the arms pivot with respect to the clamping means frame. The end of each arm carries a clamping pad 75 which may be of rubber or similar material for engagement with a sheet. A spring 76 having one end secured to an arm 74 and the other end secured to the clamping means frame or extension by a pin 77 normally pivots both of the clamping arms towards and into contact with the clamping means frame. A clamping finger 78 is pivotally mounted on each arm on a pivot 79 and will have a clamping or friction pad 80 on its end. A spring 81 connected between each arm by pin 82 and the finger propels the finger to clamping position with its end in contact with the clamping pad on the arm.

Means are provided to pivot the clamping finger to and from clamping position in contact with the clamping pad 75 (Figs. 4-9). A link 86 is provided for each finger connected at one end to its clamping finger 78 by means of a pin 87 and the other end is attached by a pin 88 to a lever 89. These levers are secured to a sleeve 90 which is pivotally or rockably mounted on the shaft 73. Pivotting of the levers relatively to the clamping arms will pull the links and pivot the clamping fingers to open position as shown in Fig. 8 and when released, the springs 81 pull each finger to closed position as shown in Figs. 7 and 9. Secured to the sleeve is an arm 91 carrying a cam follower or roller 92 which pivots the sleeve on the shaft and the levers and through the links pivot the clamping fingers to open position.

Means are provided to lock the clamping fingers 78 in open position and the means particularly shown includes a finger locking lever 94 pivotally carried on a pivot 95

mounted on one of the clamping arms. The locking lever has a locking projection and groove 96. A spring 97 connected between the locking lever and the clamping arm normally retains the clamping lever in locked or finger open position as shown in dot-dash lines in Fig. 7. The locking lever carries a release trigger 98 by means of which the finger lock may be released which is shown as an extension secured to or forming a part of the lock lever. It may extend or be bent laterally to provide easier inlocking engagement. An operating pin 99 (Fig. 3), carried by bracket 100 which is secured to the main frame, engages this release trigger or extension when a clamping means passes at pick-up position. In this position a sheet has been withdrawn far enough from a storage pocket to be clamped so that the locking lever is tripped and moved to release position. The locking shoulder or projection 96 engages a locking pin 101 carried by the finger operating lever 89 and holds this lever in finger or clamping means open position. When the locking lever 94 is shifted to the solid line position, Fig. 7, the locking pin is released whereupon the finger is moved to finger closed or clamping position under the influence of its spring 81.

The clamping means arms 74 are secured to the shaft 73 which is carried in the bearings of the extensions 72 of the clamping means frame. The spring 76 connected with one arm and with the clamping means frame propels the arms generally toward the clamping means frame so that the arms if unrestrained pivot into contact with this frame. During the travel of each clamping means on the upper level of the chain, the clamping means arms are tilted and held at an upwardly inclined angle by tilt means so that each clamping sheet being transported rests on the succeeding sheet or sheets. This prevents any untoward bending and buckling of the sheets as they lie in overlying relation and move towards the depositing platform. The tilt means extends also to the lower pass.

The tilt means (Figs. 9, 20, 21) for pivoting the arms or clamping means and holding them or it in this inclined position includes a tilt lever 104 having a roller or follower 105 at its end. The lever is an extension of one of the clamping means arms 74. Pivoting of the tilt lever and its cam follower pivots the two clamping arms, since both clamping arms are secured to the clamping means shaft. After the clamping means has passed around the upper sprocket 54 there is a tilt track 106 which is engaged by the cam follower 105 and pivots the clamping arms to the tilt position shown in Fig. 3. This tilt track is between the chains and follows in a general way or is parallel with the chains. The tilt track extends the full length of the upper level of the clamping means, continues around the sprocket shaft 58 and extends approximately half way along the lower level to approximately a gap in a cam track, which will be described. Throughout this travel, therefore, the clamping means is held tilted away from the clamping means frame. The clamping means is held secure during the opening of the clamping fingers by the tilt roller being between the tilt track and the clamping means frame. After the tilt roller rides off the tilt track the spring 76 pulls the clamping arms into contact with the clamping means frame. The clamping arms remain in this position until they have passed around the sprockets 53.

Means is provided for each clamping means to automatically keep it away from contact with the pile of sheets in its storage pocket when the clamping means is closed. If the clamping means should contact the sheet even though it is the smooth bottom surface of the clamping finger, there still is some tendency at some times to withdraw a sheet at least partially from the pocket. In order to assure that this does not occur, means are provided to hold the clamping means above the pile of sheets when the clamping means or fingers are closed.

This hold-up means include a cam roller or follower 109 carried by the tilt means lever 104. This follower is mounted for axial movement to change its axial posi-

tion from the solid line position to the dot-dash line position of Fig. 17. The cam roller has a shaft 110 slidable in a bearing 111 carried by the tilt lever. The follower is retained in the full line position by a spring 112 in a spring housing 113 which engages the end of the roller shaft. The shaft also carries a pin 114 slidable in a slot 115 in the spring housing. A cam 116 carried by a cam plate 117 is secured to the sleeve 90 so that when the clamping fingers or clamping means is closed, the follower is in the solid line position of Fig. 17. When however the sleeve 90 is turned relatively to the clamping arms 74 and tilt lever 104 to open the clamping fingers, the cam 116 moves relatively to the pin 114 and propels the pin to the left and the follower to the dot-dash position, Fig. 17 away from engagement with cam 118. If the clamping fingers are closed and the follower is in solid line position, this brings the follower in position to be engaged by a hold-up cam 118, Fig. 23, so that as the clamping means passes through pick-up position with the clamping means closed, the follower engages the cam and holds the clamping means above contact with the sheets in its pocket. If the clamping means is open, then the cam follower 109 is away from contact with the cam 118 and the clamping arms engage the top sheet in its pocket. With this hold-up means for the clamping means, the friction pad 80 on each clamping finger may be a rubber band passing around the finger.

Level means is provided to hold the clamping means in relatively level position with respect to the top of the pile of sheets at the pick-up position when a sheet is clamped as shown in Figs. 17 to 22. The clamping means here are much the same as that illustrated in Figs. 6 to 10 excepting that the clamping pad 75 on the clamping arm 74 is cylindrical and has lateral ridges around its circumference. The clamping arm carries an arcuate ratchet arm 122 which is attached to the arm such as by a screw or screws 123. The ratchet arm has ratchet teeth 124 on its lower edge. The adjacent extension 66 of the clamping means frame carries a rock lever 125 pivotally mounted on the extension on a pivot 126. This lever has a notch 127 in which notch is received the mounting bar 65. The notch is slightly wider than the diameter of the bar so that the lever will have a limited pivotal or rocking movement. A spring 128 normally propels the lever in a clockwise direction as shown in Fig. 19. This lever carries a ratchet 129 which normally is adjacent to but spaced from the ratchet teeth. A cam roller 130 is also carried by the lever on a pin 131.

When the clamping means withdraws the top sheet from a pile of sheets S in a pocket of the storage means far enough to be clamped and the clamping fingers have been released so that the edge of the sheet is clamped, the roller 130 engages a cam 134 carried by the main frame which shifts the lever 125 and brings the ratchet 129 into contact with one of the ratchet teeth 124. The ratchet engages that tooth which is adjacent the end of the ratchet when the lever is shifted. If the pile of sheets in the pocket is high, then the ratchet engages a tooth near the lower end of the ratchet lever. The clamping means is therefore held at a higher elevation or level or approximately level with the top of the pile of sheets. For a low pile of sheets in the storage pocket, the ratchet engages a ratchet tooth more distant from the end of the ratchet lever and holds the clamping means at a lower level but level or approximately level with the top of the pile of sheets. As a consequence the clamping means is retained shortly after clamping of a sheet at approximately the top of the pile of sheets in its pocket. The clamping means, therefore, is not moved towards the partition under the influence of the spring 76 as would occur without this leveling means.

Pivoting mechanism for clamping mechanism

It has been described hereinbefore that the mounting bar 65 for the clamping means is pivotally mounted be-

tween chain brackets 63 carried by the endless chains 52. Mechanism is provided to control the pivotal position of the clamping mechanism including the mounting bar and its extensions and hence the pivotal position of the clamping means. This pivoting mechanism is in addition to the tilt means. The mechanism for controlling the pivotal movement of the mounting bar and clamping means includes a cam follower plate 138 (Figs. 3, 6) secured to one end of the mounting bar. This cam plate carries a short cam follower 139 and a long cam follower 140 spaced from each other and each spaced from the mounting bar 65. The cam follower 139 operates in a cam track 141 and cam follower 140 operates in cam track 142 which control the pivotal position of the mounting bar. The short follower also engages in a cam track 143. The cam tracks can be assembled easily if the tracks and cam plate 138 are outside of the chain 52.

After a sheet has been deposited on the depositing platform, the clamping arms extend in a rearward direction or in the direction of the depositing platform. The clamping means or arms are then swung forwardly so that they will be brought into position to engage the top sheet in a pocket of the drum. This pivoting of the clamping mechanism and its clamping means is shown in Fig. 3. The long cam roller 140 is within the cam track 142 formed by spaced side walls. This cam track has a short gap 144 in one side wall in the lower pass and the wall begins again with an upwardly extending abutment 145. The cam track 141, having a pair of spaced side walls, receives the short cam roller 139 just before roller 140 reaches the gap. The track 141 extends downwardly to swing the clamping mechanism to approximately a vertical position, assisted partly by the roller 140 engaging the abutment. The cam track 141 therefore bridges the gap to control the position and pivoting of the clamping mechanism in this interval. The abutment with the descending cam track 141 swings the mounting bar through a substantial angle whereupon the track 141 terminates and the long roller enters the continuation of its cam track. The cam track 142 then has an angularly downwardly extending portion 142a which extends outside of the line of travel of the mounting bar pivots 61 and continues to swing the mounting bar as shown in Fig. 3 so that the clamping means now is projected forwardly in a substantially horizontal position or towards the storage means or drum.

As the mounting bar 65 and the clamping means pass around the sprocket 53, the cam track 142b curves inwardly towards the sprocket shaft 56 so that the clamping means retains an approximately horizontal position as the ends of the clamping arms are projected over a package of sheets S in its pocket of the drum. The curve of the cam track also turns the mounting bar 65 and hence the clamping means to bring the clamping pads 75 on the ends of the clamping arms 74 into contact with the top sheet of the package of sheets S in its pocket. This moves the clamping arms away from contact with the clamping means frame or extensions 66 so that the spring 76 presses the pads against the top sheet. As the pads and clamping means move away from the pocket by the divergent paths of the clamping means and the pocket, the top sheet is drawn outwardly and the clamping finger locking lever 94 is released whereupon the fingers close and clamp the sheet between the arm pads and the fingers. The finger locking lever is released when the trigger 98 passes by and is engaged by the operating pin 99.

The endless chain assumes a straight or approximately a straight path between the two sprockets 53, 54, between which the cam track 142 in portion 142c is straight and has but a single wall. The spring 76 restores the clamping means into contact with the clamping means frame. The cam track 142b ends between the sprockets 53 and 54 and at the same moment or shortly thereafter the short roller 139 enters the arcuate cam track 143

which retains the clamping means in substantially horizontal position for a portion of its travel. This cam track curves around the shaft 57 and inwardly towards the shaft of the sprocket so that as the mounting bar 65 passes around the sprocket 54, the clamping means is tilted angularly upwardly and the cam track terminates. Just before the cam track 143 terminates, the long roller has entered the mouth of the cam track 142 and retains the mounting frame in substantially horizontal position. This track continues to the sprocket 55 (Fig. 4) where the cam track moves outwardly and then follows a curvature having the center of the sprocket shaft as a center for a substantial distance around the sprocket shaft where it continues on as the cam track for the lower pass. Because of the change of direction of the endless chain, the clamping means changes from a forward direction to a rearward direction and carries the sheet carried by the clamping means adjacent to a pile of sheets on a depositing platform 146 where the sheet is released. With the cam followers of different lengths and hence with the edges of the cam tracks in different vertical planes, there will be no interference between the cam followers as the respective cam tracks take over control of the pivotal movement of the clamping mechanism and hence the clamping means. The cam tracks are suitably secured to the main frame 26.

Selective opening means

In the construction illustrated herein, the clamping means is opened at one of two positions so that groups of sheets are piled on a depositing platform in staggered or spaced relation lengthwise but with the edges in alignment. Each group or set of segregated or staggered sheets can readily be separated from the other groups. The change in the time or position of the opening of the clamping means occurs in the lower level or pass of the clamping means after the latter has passed around the sprocket 55.

The opening of the clamping means is accomplished by an opening plate 148 (Figs. 4, 5) pivotally mounted on a pivot 149, mounted on a part of the main frame 26 such as a cross bar or bars thereof. This opening plate has a pair of spaced opening planes or surfaces 150a and 150b. With the opening plate in the position shown in Fig. 4, the opening roller 92 carried by the clamping means sleeve 90 engages the opening plane 150a as the clamping means moves forwardly with respect thereto and swings the roller and sleeve relatively to the clamping arms which opens the clamping fingers as described. Pivoting of the opening plate to the position shown in Fig. 5 moves or lifts the opening plane 150a away from engagement by the opening roller 92 whereupon this roller engages the opening plane 150b or at a later time or position as to opening relatively to opening plane 150a.

The opening plate is shifted from one position to the other by shifting an operating plate 152, Fig. 15 secured to a pivot 151 mounted on the main frame. This operating plate carries a stop 153 which engages a pair of spaced stop abutments 154 carried by the main frame. This operating plate carries a pair of spaced pins 155 and 156 one on each side of the pivot. The pin 155 is engaged by a shoulder 158 on one side of a pull member 157. A similar shoulder 159 is provided for the pin 156 on the other side. A spring 160, attached to the end of a lever 166 and to the pull member, holds the edge of the pull member against the pin so that the pin is received against its shoulder when the member is pulled. The pull member is connected with the armature of a solenoid 161 so that energization of the solenoid pulls the pull member downwardly so that the operating pin 155 engages its shoulder 158 and is pulled down. This swings the operating plate 15 to the position shown in the figure which pivots the operating plate therewith. The spring 160 now pulls the pull member upwardly and pulls the other edge of the pull member into contact with

the operating pin 156. The spring 160 performs a double function namely in pulling the pull member upwardly and pulling the latter to the proper side. A second operation of the solenoid again pulls the pull member downwardly so that the pin 156 engages its shoulder 159 and pulls the operating plate to its other or first position. A guide bracket 162 may be provided for the pull member or rod.

Means are provided to hold the operating plate 152 in either of its operated positions which means includes a lever 166 which is pivotally mounted on the frame 26 by a pivot 167. A spring 168 is connected between the end of the lever and another part which may be the guide bracket 162. This lever is connected with the operating plate through a pin 169 carried by the plate and engaging in a slot 170 in the adjacent or other end of the lever 166 so that the lever is pivoted with the plate but in opposite directions. When the operating plate is pivoted to its other position, the lever swings or pivots in an opposite direction or to the left of center line between pivots until the spring passes over the pivot center line whereupon the spring assists in propelling the operating plate to its other position and holds it and the vane in this position. A second operation of the solenoid reverses the operation and carries the lever and spring to the other side of dead center or the pivot center line as illustrated so that the spring both partly operates the plate and holds the plate in each of its two positions. The pivoting of the lever 166 also controls the pull or position of spring 160 so that the pull member is shifted to the opposite side to engage the upper pin 155 or 156.

The operating plate 152 is connected with the opening plate 148 through links 171 and 172, and a lever 173. The lever 173 is fixed to a shaft 163, Fig. 5, which shaft carries a lever 164. A link 165 connects the lever 164 with the opening plate 148. Oscillation of the operating plate 152 to and from its two positions, oscillates the shaft 163 and lever 164 to move the opening plate to and from its two positions shown in Figs. 4 and 5.

Control means

Control means are provided to operate the opening means whereby the clamping means is opened at a selected one of two positions. Control means are also provided to selectively close desired clamping means in the lower passage or level of the movement of the clamping means from or between depositing position to pick-up position. These control means are embodied in one unit which includes preferably a disk 174 (Fig. 2) driven by the machine such as a chain 175, a sprocket 176 on the drum shaft 28 and a sprocket 178 secured to a shaft 179 mounted on the main frame so that the disk rotates at the same speed as the drum, that is each makes one revolution in the same time. The disk has three circular rows of holes 180, 181, 182 concentric with the center of the disk. There is one such hole in each circle of holes for each pocket of the storage drum and hence for each clamping means of the machine. This control means may be connected with any driven part of the collating machine such as the drive connection or the sprockets for the endless chains for the clamping means. Since, however, it is more convenient to relate it with the pockets of the drum, it is adjacent to the drum and mounted on the main frame at the operating side of the drum.

An operating or contact screw or pin is inserted in a hole corresponding with a pocket in the drum and hence with the clamping means for that pocket which is to be controlled. Any series of holes may control the desired part of the collating machine. The outer circle of holes has been selected for controlling the number of pages in each book or booklet. That is a control pin or screw 185 (Figs. 2, 15) in a hole or pressed inwardly shifts the opening plate 148 for the clamping means to one of its positions to open one or more of the clamping means

at one position as each passes the opening plate. The control pin or screw is inserted or advanced in the hole at the position in which the opening plate is to be shifted. In other words, if there are two empty holes between succeeding operating pins or screws, or unpressed pins, then the opening plate is shifted for every third clamping means. Hence three successive clamping means are opened at the same position as they pass the opening plate. Three pages are therefore off-set at one position upon the depositing platform. The screws in this circle close a switch 186 which energizes the solenoid 161 for changing the position of the opening plate for the clamping means. The next screw or depressed screw again closes the switch which again energizes the solenoid and operation of the solenoid restores the opening plate to its first position and the clamping means are then opened at the other position. Each succeeding control pin or succeeding depressed pin therefore changes the position of the opening plate.

10 The position of the opening plate for the clamping means may be shifted once for each revolution in which event the sheets picked from all of the pockets are positioned in one position and the sheets in all of the pockets in the next revolution of the drum are positioned in the other position. A control pin or screw in each hole or depressed in each hole shifts the opening plate for each clamping means passing the plate so that each page is alternately positioned. Any other arrangement may be made such as for a fifty pocket drum, there may be five changes of ten sheets each. Likewise the control means may be set for different numbers such as 6, 8, 10, 15 and 21 or any other arrangement.

Selecting means

35 The inner circle of holes 182 receives one or more control pins or screws 189 (Fig. 2) to operate a switch 190 (Fig. 16) when it passes the same in the rotation of the control disk 174. It will be recalled that the clamping means is opened to deposit its sheet in depositing position and it is locked in open position. This switch 190 is connected with a solenoid 191 which moves a tripper 192 to its dot-dash position in Fig. 3 for engaging the lock release lever or trigger 98 for the clamping fingers at the lower level or pass of the clamping means. Operation of the lock release lever closes the clamping fingers so that when the clamping means pass into the drum pocket they do not pick up or clamp a sheet in the pocket.

40 The tripper operating means includes a tripper plate 196 secured to the shaft 193 and connected with the solenoid 191 by a suitable pin connection 197 carried by the plate. Energization of the solenoid 191 pulls the tripper to the left from the solid line position shown in Figs. 3, 16. The tripper plate has a notch 198 and a stop 199 so that when the tripper plate is pulled to the left, a roller 200 rides over a surface 201 and is pulled into the notch by a spring 202 to releasably or resiliently retain the roller in the notch. The stop 199 is engaged by the roller so that it does not override the notch. A second solenoid 203 is also connected to the tripper plate by a pin 204 carried by the plate so that when energized it pulls the tripper plate and the tripper 192 to the right or to the solid line position of Fig. 3. In this position the clamping means remain open to grip a sheet in its pocket of the drum.

45 The middle circle of holes 181 receives one or more control screws or pins 207 which when each passes a switch 208 it closes its contacts and this energizes the solenoid 203 to swing the tripper away from the path of travel of the release lever for the locking means for the clamping finger as shown in solid lines in Fig. 3. In this position of the tripper the locking lever for each clamping means or clamping fingers is not engaged as it passes so that the clamping fingers or clamping means remains

open. When the clamping means enters a pocket of the drum at the pick-up position, a sheet is picked up.

With this control means and tripper, the sheet in any pocket or pockets may be selectively picked up or passed by the clamping means as desired. One purpose of this control or rejection of sheets may be desirable for example if one book or group of sheets includes pages 1 to 20 and the next booklet may have the same pages from 1 to 15, excluding pages 16 to 20. Obviously any desired selection or rejection of sheets from any particular pocket or pockets may be made.

It has been stated that a control screw or pin may be inserted in any desired hole of the control disk. It is clear that each hole may have a screw (as shown) or pin inserted or screwed farther into the hole to bring it into contact with its respective switch or withdrawn outwardly so that it does not contact its switch. Likewise either the control disk may rotate and the switches be fixed, as particularly illustrated, or the disk may be fixed and the switches or switch means rotate. It is necessary only that the disk or the switches rotate with respect to the other.

Sheet abutment means

In conjunction with the clamp opening means there is provided sheet abutment means for each of the two or stagger positions of the sheets on the depositing table or platform. The abutment means for the forward position includes a fixed sheet abutment 211 against which the forward edge of each sheet is positioned when the clamping means is opened by the second opening surface 150b. In conjunction with this fixed abutment there is provided a movable sheet abutment 212 for engaging the other or rear edge of each sheet so that the sheet is positively positioned. This movable abutment is pivoted on the frame (Fig. 11) on a pivot 213 and the abutment is moved or raised from abutting position, shown in dot-dash lines, to remote or clear position, shown in solid lines, by a solenoid 214, the armature of which is connected by a link 215 to a pin 216 on the abutment. When the solenoid is deenergized, the abutment returns by gravity to abutting position. When the clamping means is opened in forward or later position to release a sheet, the position of the sheet is determined by the fixed forward abutment 211 and the movable rear abutment. The movable abutment is moved alternately from abutting position to a remote position or a position away from abutting position in timed sequence with the opening plate.

The solenoid 214 is energized or under the control of a switch 218, Fig. 15, having a contactor 219 which is shifted to close the switch by a depression 220 in the periphery of the operating plate 152 which forms a cam. When the opening plate is in the position of Fig. 5 to open the clamping means in forward position, the switch contactor is out of the depression and riding on the periphery of the operating plate which opens switch contacts 221, 222 to deenergize the solenoid and the movable abutment 212 moves downwardly by gravity into abutting position. When the contactor is in the depression and the opening plate 148 is in down position of Fig. 4 the contacts 221, 222 are closed which energizes the solenoid upwardly to pull the abutment upwardly to remote position. This abutment therefore is operated from the means for shifting the opening plate and may be operated therefrom by any suitable means, the electrical form illustrated being preferred. The abutment 212 may have a recess 224 to pass a fixed frame 225 for the side of the sheets.

When the opening plate is in down position so that surface 159a controls the opening of the clamping means in rear or early position, a pair of abutments are also used. The forward abutment in this stagger position of the sheets, is movably and pivotally mounted on a pivot 227 carried by a bracket 228 secured to the main frame or forming a part of the abutment 211. It is

connected by a link 229 to a lever 230 which lever is pivotally mounted on the frame on a shaft or pivot 231. The shaft 231 carries a lever 232, and the end of this lever is connected with the clamp opening means at the junction of the two links 171, 172 so that it is connected with both the opening plate 148 and the operating plate 152. A fixed sheet abutment 233 cooperates with the movable abutment 226 and is spaced approximately the length of a sheet from the movable sheet abutment.

Gaging means

The collating machine is provided with means which gages the number of sheets or thickness of a sheet being transported by each clamping means so that if two or more sheets are or a thicker sheet is being transported, the machine is automatically stopped so that the extra or thick sheet may be removed. This gaging means is, therefore, located in a position where the clamping means carries or is transporting a sheet to be collated. It also gages "on the fly" or while the sheets are in motion or being transported without stopping the sheet movement. In the machine illustrated, the gaging takes place in the upper pass of the clamping means and, for reasons which will appear, is located adjacent the sprocket wheel 55.

In order to assure that the sheet or sheets gaged by the gaging means is that being transported by a single clamping means, means are provided to separate the sheet or sheets carried by one clamping means as it passes the gaging means from a sheet or sheets carried by a following or preceding clamping means which may and usually does overlap. The sheet separating means, Fig. 11, includes a scroll 238 mounted on the periphery of a rotating housing 239. The scroll circles the housing about one and one quarter times so that there is some overlapping of the ends. The scroll has also an additional portion 238a forming a taper sheet receiving channel or narrow throat at a gap in the scroll. This rotating housing rotates on a vertical axis on stub shafts 240 at each end which are mounted in bearings carried by the main frame 26. Any suitable drive connection may be used to rotate the housing that is shown including a pinion 241 secured to the lower stub shaft which pinion meshes with a gear 242 secured on a shaft 243 mounted in the main frame. A bevel gear 244 is also secured to this shaft which bevel gear meshes with a bevel gear 245 secured on the sprocket shaft 58. The gear ratio is such that the rotary housing rotates once in the time that it takes one clamping means to pass thereby.

As a clamping means passes the scroll, the edge of the sheet carried thereby enters the space between spaced scroll portions and as the scroll rotates it separates or raises this sheet from the underlying sheet carried by the next following clamping means. When the scroll rotates a full revolution, the lower level or the lower portion of the scroll turns beneath the edge of the next sheet or in a position to receive the next sheet and raise it above the next following sheet. The scroll portion 238a forms a throat which also directs the edge of the sheet or sheets between contacts of a gaging means which gages the sheet or sheets carried by one clamping means.

The gaging means includes a movable contact 248 and a second movable contact 249 spaced from the first contact by the thickness of one sheet. The first movable contact is carried on an arm 250 mounted on a pivot 251 carried by the rotary housing. This arm also carries a cam follower 252, Fig. 12, which is in contact with a stationary cam 253. As the rotary housing turns, the cam follower rides off of the high point of the cam which separates the two contacts so that a sheet may be inserted easily therebetween. When the contacts make about a complete rotation and has the edge of a sheet projected therebetween, the cam follower rides up on the high point of the cam against the tension of a spring 247 and pivots the first movable contact towards the second movable contact. If there are two sheets between the contacts,

the second contact is raised sufficiently to close a microswitch 254 completing a circuit to a slip ring 255 and its brush 256. Closing of this switch and its electrical circuit operates a solenoid 257, Fig. 24, which opens a throwout switch 258 in series with the machine motor and stops the machine. The inertia of the machine carries the clamping means with its two or more sheets to the depositing position or platform and deposited the two sheets so that the extra sheet need merely be removed from the pile. This gaging means of course will function to stop the machine if a sheet of greater thickness than the usual sheet has been picked up by the clamping means.

A somewhat similar scroll 260 is provided on the opposite side of the sheet. This scroll is secured to the periphery of a rotary cylinder 261 carried by a shaft 262 rotatably mounted in the auxiliary frame 26a. The scroll extends around about $1\frac{1}{4}$ of the periphery of the cylinder so that it has overlapping spaced ends. This scroll rotates in a counter clockwise direction or at the sheet edge in the direction of the travel of the sheet. As a clamping means carries a sheet past this scroll the edge of the sheet enters between the spaced overlapping portions of the scroll and as the scroll rotates the sheet edge rides on the scroll and is raised therewith and above the sheet carried by the following clamping means. This scroll is also rotated at a speed the same as the scroll 238 through a suitable connection. The connection shown includes a bevel gear 263 secured to the shaft 262. This gear meshes with a bevel gear 264 which is keyed to a shaft 265. This shaft carries a sprocket 266 on which is carried a chain 267, and the chain is driven by a sprocket 268 secured to the sprocket shaft 58.

This sheet separating means preferably is adjustably mounted on the frame to accommodate for different widths of sheets. To this end the scroll frame 26a is mounted on ways 271 carried by the main frame so that the separating means may be shifted left and right on the ways. A clamp plate 272 engages the ways and locks the sliding scroll frame 26a to the ways by means of a screw 273. The bevel gear 264 is keyed to the shaft in known manner so that it may slide along the length of the shaft and still be driven by the shaft.

Detector means

Means are provided also to stop the machine in the event a clamping means should fail to pick-up a sheet from its pocket. This detector means is conveniently associated with the gaging means (Figs. 11, 12, 13, 24) and includes a detector switch comprising a fixed contact 276 but preferably flexibly mounted on a spring support 277 carried by the rotatable housing 239. A movable contact 278 is conveniently carried by the pivotal arm 250 so that the movable contact also is moved into contact with the fixed or flexible contact by the cam 253. When the cam follower reaches the high point of the cam and the edge of a sheet has been projected between the two contacts 278, 276, the sheet prevents engagement and closing of the switch formed by the two contacts and nothing happens. If, however, a sheet is missing, the movable contact engages the fixed contact and a circuit is established through a ring 279 and its brush 280 to operate a solenoid 281 at a throwout switch 282 which opens the switch and stops the machine. The inertia of the machine carries the clamping means to or beyond the depositing point so that the missing sheet can be inserted in proper position in the pile. The gaging switch and the detector switch may have a joint, ground or negative connection through a slip ring 284 and its brush 285.

It is not necessary to provide two throwout switches 258 and 282 since a single switch will accomplish the stopping of the machine; however, two are disclosed since this reveals in one way whether a missing sheet or two sheets is the cause of the stopping of the machine. Such switches customarily have a light as a part of the switch which lights when the switch is opened. This tells which switch has opened and tells the operator to insert a miss-

ing sheet or remove one of two sheets. The throwout switches may take several forms. In the switches illustrated the solenoid releases a catch 283 which holds the switch contacts closed so that release of the catch opens the switch. A manual button is pressed to close the switch when correction has been made in the sheet pile.

It has been described that the clamping means may be controlled through the selecting means in which the trip-per 192 releases the locking means for the clamping fingers which closes the clamping means so that a sheet is not picked up from its pocket in the storage drum. This is an intentional omission of a sheet in the clamping means and hence when this occurs, the detector means should become inoperative. This is accomplished by including a normally closed nullifying switch 287 in series with the detector switch 276, 278. This nullifying switch is conveniently operated from the control disk 174. When a control pin 189 operates the solenoid 191 to close a clamping means so that it will not pick-up a sheet, this control pin remains depressed and will also open the nullifying switch 287. This latter switch is located with respect to the positions of the control disk so that when the closed clamping means reaches the detector position the nullifying switch is opened. As a consequence the fact that there is a missing sheet does not operate the throwout switch and does not stop the machine. It will be noted therefore that depression of a pin 189 to close a clamping means functions without more or any additional operation to open the nullifying switch.

Any form of depositing device may be used upon which the sheets are deposited. The depositing device particularly shown is a platform 146 having feed means to move the platform downwardly. The downward movement is under the control of a feeder finger which is periodically brought into contact with the top sheet of the pile on the platform through mechanism driven from a link 223 connected off center to a collar carried by the sprocket shaft 58. If the pile is too high, the finger does not descend as far which trips a feed mechanism and the table is lowered until the greater descent of the trigger finger disconnects the feed mechanism.

The endless means or chains 52 have a driving connection with the motor 29 or with the storage means or drum or particularly the gear reduction unit 30 such as a chain 297 with suitable sprockets. The sharper curve in the cam track 142 at the rear sprocket flips the sheet rearwardly as the clamping means pass around the sprocket so that the sheet is laid flat on the depositing platform.

Preferably the position (Fig. 12) of the cam 253 is adjustable so that the spacing between the gaging contacts 249 and 250 may be conveniently adjusted. This adjusting means includes a cam slide 290 slidable in ways 291, the slide having an enlarged opening 292 for the shaft 240. An adjusting screw 293 turnably carried by the frame 26 is used to adjust the position of the cam.

This invention is presented to fill a need for improvements in a collating machine. It is understood that various modifications in structure, as well as changes in mode of operation, assembly, and manner of use, may and often do occur to those skilled in the art, especially after benefiting from the teachings of an invention. This disclosure illustrates the preferred means of embodying the invention in useful form.

What is claimed is:

1. A collating machine comprising a main frame, storage means carried by the main frame having a plurality of pockets and movable to bring the pockets successively to pick-up position where sheets are removed from the pockets, a depositing platform, a plurality of clamping mechanisms each including sheet clamping means, endless means mounting the clamping mechanisms in spaced relation and for movement from adjacent the depositing platform to pick-up position and return, means

to close the clamping means at a pocket at pick-up position, opening means to open the clamping means at the depositing platform at one of two spaced positions, control means selectively controlling the opening means for the clamping means to open the same alternately at the two positions to stagger sets of sheets of one or more sheets, and driving mechanism connecting the storage means and the endless means.

2. A collating machine as in claim 1 including forward abutment means at the depositing platform having a stationary forward abutment and movable rear abutment, rear abutment means at the depositing platform having a movable forward abutment and a stationary rear abutment, the movable abutments moving to and away from abutting position, and means connecting the movable abutments with the opening means for operation thereby into abutting position alternately with the movable rear abutment moving into abutting position for opening of the clamping means in forward position.

3. A collating machine as in claim 1 in which the opening means includes a cam follower carried by the clamping means and an opening plate pivotally mounted on the main frame in the path of the cam follower for movement to and from two positions and having a forward opening surface adjacent the pivot and a rear operating means connected with the opening cam plate to pivot the same alternately from one to the other position.

4. A collating machine as in claim 3 in which the operating means for pivoting the opening plate includes an operating plate mounted on a pivot on the main frame for oscillation and having a pair of pins on opposite sides of the pivot, a pivoted pull rod having a shoulder for each pin spaced from each other a distance less than the spacing of the pins, means to shift the pull rod for alternate engagement of each shoulder with its pin, means connected with the pull rod to pull the same and the control means controlling its operation.

5. A collating machine as in claim 4 in which the means to pull the pull rod is a solenoid, and the control means is a switch means connected with the solenoid and a plurality of switch closing means, one of said means being mounted for movement relatively to the other means, and means connecting the movable means with the driving mechanism.

6. A collating machine as in claim 4 in which the means for shifting the pull rod includes an oscillating lever pivotally mounted on the frame between its ends adjacent to the operating plate and connected therewith at one end to oscillate as the operating plate oscillates, a spring connected between the other end of the lever and the pull rod.

7. A collating machine as in claim 3 including a forward abutment means at the depositing platform having a stationary forward abutment and a movable rear abutment movable to and from abutting position, rear abutment means at the depositing platform spaced from the forward abutment means having a movable forward abutment movable to and from abutting position, and a stationary rear abutment, and means connecting the movable abutments with the operating means for the opening plate to move the movable abutments alternately into abutting position.

8. A collating machine as in claim 7 in which the connecting means for the movable abutment of the forward abutment means includes a solenoid connected with the abutment, a switch connected with the solenoid, and a cam on the operating plate opening and closing the switch.

9. A collating machine as in claim 2 including a clamping means frame having a pivot pivotally mounting the frame on the endless means and a shaft spaced from the frame pivot and pivotally mounting the clamping means, and swing means adjacent the passage of the

clamping means from the depositing platform to the pick-up position and operating the clamping means frame to pivot the clamping means from a position rearwardly to a position forwardly.

5 10. A collating machine as in claim 9 in which the swing means includes cam follower means carried by the clamping means frame and cam track means carried by the main frame and receiving the cam follower means.

10 11. A collating machine as in claim 10 including cam track means adjacent the pick-up means to receive the cam follower means and swing the clamping means frame to bring the clamping means into contact with a sheet in a pocket.

15 12. A collating machine as in claim 9 including a cam follower carried by the clamping means and a tilt track in the path of the cam follower and engaged by the cam follower to tilt and hold the clamping means.

13. A collating machine comprising a main frame, 20 storage means carried by the main frame having a plurality of pockets and movable to bring the pockets successively to pick-up position where sheets are removed from the pockets, a depositing platform, a plurality of clamping mechanisms each including sheet clamping

25 means having open and closed positions, endless means mounting the clamping mechanisms in spaced relation and for movement from adjacent the depositing platform to pick-up position and return, means to close the clamping means at a pocket at pick-up position, means to

30 open the clamping means at the depositing platform, driving mechanism connecting the storage means and the endless means, gaging means located adjacent the path of movement of the clamping means in a position to engage the faces of a sheet or sheets carried by each 35 clamping means adjacent an edge of the sheet, and means operated by the gaging means when more than one sheet is carried by a clamping means to stop the driving mechanism.

14. A collating machine as in claim 13 including means 40 adjacent the gaging means to separate the sheet carried by each clamping means from an adjacent sheet.

15. A collating machine as in claim 13 in which the gaging means includes a first movable contact, a second movable contact movable to a position spaced from the first contact a distance the same as the thickness of a sheet, means rotating the contacts towards and away from the path of the edge of the sheet and rotating once for each clamping means, means connected with the second contact to move the same towards and away from the first contact once for each revolution, and means responsive to the movement of the first contact to stop the machine.

16. A collating machine as in claim 15 in which the means responsive to the movement of the first contact includes a gaging means switch which is closed by movement of the first contact, throwout switch means controlling the driving mechanism and the gaging means switch being connected with the throwout switch means to open the same.

60 17. A collating machine as in claim 14 including scroll means mounted with the gaging contacts and rotatable therewith to direct the edge of the sheet between the contacts and to separate the sheet from the following sheet.

18. A collating machine comprising a main frame, 65 storage means carried by the main frame having a plurality of pockets and movable to bring the pockets successively to pick-up position where sheets are removed from the pockets, a depositing platform, a plurality of clamping mechanisms each including sheet clamping means having open and closed positions, endless means 70 mounting the clamping mechanisms in spaced relation and for movement from adjacent the depositing platform to pick-up position and return, means to close the clamping means at a pocket at pick-up position, means to open 75 the clamping means at the depositing platform, driving

mechanism connecting the storage means and the endless means, sheet detector means adjacent the path of movement of the clamping means in a position to engage the edge of a sheet or sheets carried by each clamping means, and means operated by the sheet detector means to stop the driving mechanism when a sheet is missing in a clamping means.

19. A collating machine as in claim 18 including means adjacent the detector means to direct the edge of each sheet into operative relation with the detector means and to separate the edge of a sheet carried by each clamping means from the preceding sheet.

20. A collating machine as in claim 18 including means to selectively close one or more clamping means after opening the same at deposit position and prior to arriving at pick-up position adjacent the storage means, and means rendering the sheet detector means inoperative at the time that said prior closed clamping means reaches the detector means.

21. A collating machine as in claim 18 in which the sheet detector means includes a pair of detector switch contacts, means rotating the detector switch contacts towards and away from a position adjacent the clamping means into the path of the edge portion of a sheet carried by each clamping means, means mounting one detector switch contact for movement into contact with and away from the other detector contact, means moving the movable contact into contact with and away from the other contact once for each revolution thereof, and throw-out switch means controlling the driving mechanism and connected with a detector switch contact to open the throw-out switch means and stop the machine when the contacts engage.

22. A collating machine as in claim 21 in which the clamping means includes at least one pivoted clamping finger, spring means propelling the clamping finger to closed position, locking means to hold the clamping finger in open position, release means located adjacent the path of movement of the clamping means between depositing position and pick-up position and movable to and away from a position to release the locking means and close the clamping means, operating means connected with the release means to move the same to releasing position, operating means connected with the release means to move the same away from releasing position, and control means selectively controlling the operation of the operating means and rendering the detector means inoperable.

23. A collating machine as in claim 22 in which each operating means for the release means includes a solenoid; the control means includes a switch for each solenoid, a set of switch operators for each solenoid, and each set including an operating pin for each pocket of the storage means, control drive means connected with one of the parts including the switches and switch operators to drive one part relatively to the other and at the speed of the storage means, and a switch in series with the detector switch and located to be operated by the switch operator for the switch which controls the movement of the release means to release position.

24. A collating machine comprising a main frame, storage means carried by the main frame having a plurality of pockets and movable to bring the pockets successively to pick-up position where sheets are removed from the pockets, a depositing platform, a plurality of clamping mechanisms each including sheet clamping means, endless means mounting the clamping mechanisms in spaced relation and for movement from adjacent the depositing platform to pick-up position and return, means to close the clamping means at a pocket at pick-up position, means to open the clamping means at the depositing platform, driving mechanism connecting the storage means and the endless means, gaging means located adjacent the path of movement of the clamping means in a position to engage the faces of a sheet or

sheets carried by each clamping means adjacent an edge of the sheet, and means operated by the gaging means when more than one sheet is carried by a clamping means to stop the driving mechanism, sheet detector means adjacent the path of movement of the clamping means in a position to engage the edge of a sheet or sheets carried by each clamping means, and means operated by the sheet detector means to stop the driving mechanism when a sheet is missing in a clamping means.

25. A collating machine as in claim 24 including a housing mounted for rotation adjacent the path of movement of the clamping means, means connected with the housing to rotate the same one revolution for each clamping means passing the housing, the gaging means and detector means being carried by the housing and rotating therewith, scroll means carried by the housing to separate the sheet carried by a clamping means and to direct the edge of the sheet into position for engagement by the gaging means and the detector means.

26. A collating machine as in claim 25 in which the gaging means includes a first movable gaging contact and a second movable gaging contact movable to a position spaced from the first contact a distance the same as the thickness of a sheet, means mounting the first gaging contact for movement towards and away from the other, a switch carried by the housing and operable by movement of the first contact, means connected with the switch to stop the driving mechanism, the detector means including a first switch contact and a second switch contact forming a detector switch, means connected with a switch contact to stop the driving mechanism when the detector switch is closed, and means connected with the two second contacts to move the same towards and from the first contacts once for each revolution of the housing.

27. A collating machine as in claim 26 in which the means for moving the second contacts is a stationary cam and a cam follower connected with the second contacts and engaging the cam.

28. A collating machine as in claim 27 including means to move the cam to adjust the movement of the second contacts.

29. A collating machine as in claim 25 including a second scroll means in alignment with the housing and located to separate the other edge of each sheet and means connecting the second scroll with the endless means to rotate the scroll.

30. A collating machine comprising a main frame, storage means carried by the main frame having a plurality of pockets and movable to bring the pockets successively to pick-up position where sheets are removed from the pockets, a depositing platform, a plurality of clamping mechanisms each including a clamping means frame and a sheet clamping means pivotally mounted on the clamping means frame, endless means mounting the clamping mechanisms in spaced relation and for movement from adjacent the depositing platform to pick-up position and return, means to close the clamping means at a pocket at pick-up position, means to open the clamping means at the depositing platform, means to selectively close the clamping means during its movement between the depositing platform and pick-up position, a lifting cam adjacent pick-up position, a cam follower carried by the clamping means movable to and from a position for engagement with the lifting cam, means operated by the clamping means in closed position to move the cam follower to a position to engage the lifting cam, and driving mechanism connecting the storage and the endless means.

31. A collating machine as in claim 30 in which the cam follower is mounted on the clamping means for axial movement to and from a position in the path of the lifting cam, means carried by the clamping means to close the same including a pivoted lever and a cam carried by the pivoted lever and engaging the cam follower to

move the latter axially away from engagement with the lifting cam when the clamping means is open.

32. A collating machine comprising a main frame, storage means carried by the main frame having a plurality of pockets and movable to bring the pockets successively to pick-up position where sheets are removed from the pockets, a depositing platform, a plurality of clamping mechanisms each including a clamping means frame and sheet clamping means pivotally mounted on the clamping means frame, endless means mounting the clamping mechanisms in spaced relation and for movement from adjacent the depositing platform to pick-up position and return, means to close the clamping means at a pocket at pick-up position, means to open the clamping means at the depositing platform, leveling means carried by the clamping means to hold the latter at the level of the pile of sheets in a pocket when the clamping means engages the top sheet in a pocket, and driving mechanism connecting the storage means and the endless means.

33. A collating machine as in claim 32 in which the leveling means includes a ratchet carried by the clamping means and having a plurality of notches, a pawl carried by the clamping means frame and normally spaced from the ratchet and movable into contact with the ratchet, and means carried by the main frame to move the pawl into contact with the ratchet when the clamping means engages a sheet in its pocket.

34. A collating machine as in claim 32 in which the leveling means includes an arcuate ratchet carried by the clamping means, having a plurality of notches, a pawl pivotally mounted on the clamping means frame and normally spaced from the ratchet and movable into contact therewith, a cam carried by the main frame adjacent the path of movement of the pawl when the clamping means engages the top sheet in a pocket and pivoting the pawl into engagement with a notch on the ratchet.

35. A collating machine comprising a main frame, storage means carried by the main frame having a plurality of pockets and movable to bring the pockets successively to pick-up position where sheets are removed from the pockets, a depositing platform, a plurality of clamping mechanisms each including sheet clamping means, endless means mounting the clamping mechanisms in spaced relation and for movement from adjacent the depositing platform to pick-up position and return, means to close the clamping means at a pocket pick-up position, opening means to open the clamping means at the depositing platform at one of two spaced positions, control means selectively controlling the opening means for the clamping means to open the same alternately at the two positions to stagger sets of sheets of one or more sheets, driving mechanism connecting the storage means and the endless means, gaging means located adjacent the path of movement of the clamping means in a position to engage the faces of a sheet or sheets carried by each clamping means adjacent an edge of the sheet, and means operated by the gaging means when more than one sheet is carried by a clamping means to stop the driving mechanism.

36. A collating machine as in claim 35 in which the means operated by the gaging means includes a gaging means switch, and a throwout switch means controlling the driving mechanism connected with the gaging means switch to open the throwout switch means.

37. A collating machine as in claim 36 including scroll means to direct the edge of a sheet carried by a clamping means into the gaging means.

38. A collating machine comprising a main frame, storage means carried by the main frame having a plurality of pockets and movable to bring the pockets successively to pick-up position, a depositing platform, a plurality of clamping mechanisms each including sheet clamping means, endless means mounting the clamping mechanisms in spaced relation and for movement from adjacent the depositing platform to pick-up position and return, means

to close the clamping means at a pocket at pick-up position, opening means to open the clamping means at the depositing platform at one of two spaced positions, control means selectively controlling the opening means for the clamping means to open the same alternately at the two positions to stagger sets of sheets of one or more sheets, driving mechanism connecting the storage means and the endless means, sheet detector means adjacent the path of movement of the clamping means in a position to engage the edge of a sheet or sheets carried by each clamping means, and means operated by the sheet detector means to stop the driving mechanism when a sheet is missing in a clamping means.

39. A collating machine as in claim 38 in which the detector means includes a pair of switch contacts forming a detector switch, and the means operated by the sheet detector includes a throwout switch means connected with the driving mechanism, and the detector switch being connected with the throwout switch means to open the latter.

40. A collating machine as in claim 39 including scroll means to direct the edge of a sheet carried by a clamping means between the detector switch contacts.

41. A collating machine as in claim 39 including locking means to hold the clamping means open, release means movable to and from a position to engage and release the locking means and located between the opening means and pick-up position, control means selectively controlling the movement of the release means, a second switch in series with the detector switch and normally closed, and the control means opening the second switch when a clamping means closed by the release means passes the detector switch.

42. A collating machine comprising a main frame, a storage means carried by the main frame having a plurality of pockets and movable to bring the pockets successively to pick-up position where sheets are removed from the pockets, a depositing platform, a plurality of clamping mechanisms each including sheet clamping means, endless means mounting the clamping mechanisms in spaced relation and for movement from adjacent the depositing platform to pick-up position and return, means to close the clamping means at a pocket at pick-up position, opening means to open the clamping means at the depositing platform at one of two spaced positions, control means selectively controlling the opening means for the clamping means to open the same alternately at the two positions to stagger sets of sheets of one or more sheets, driving mechanism connecting the storage means and the endless means, gaging means located adjacent the path of movement of the clamping means in a position to engage the faces of a sheet or sheets carried by each clamping means adjacent an edge of the sheet, means operated by the gaging means when more than one sheet is carried by a clamping means to stop the driving mechanism, sheet detector means adjacent the path of movement of the clamping means in a position to engage the edge of a sheet or sheets carried by each clamping means, and means operated by the sheet detector means to stop the driving mechanism when a sheet is missing in a clamping means.

43. A collating machine as in claim 42 in which the means operated by the gaging means includes a gaging means switch, and a throwout switch means controlling the driving mechanism connected with the gaging means switch to open the throwout switch means.

44. A collating machine as in claim 42 including scroll means to direct the edge of a sheet carried by a clamping means into the gaging means.

45. A collating machine as in claim 42 in which the detector means includes a pair of switch contacts forming a detector switch, and the means operated by the sheet detector includes a throwout switch means connected with the driving mechanism, and the detector switch being connected with the throwout switch means to open the latter.

21

46. A collating machine as in claim 42 including scroll means to direct the edge of a sheet carried by a clamping means between the detector switch contacts.

47. A collating machine as in claim 42 including locking means to hold the clamping means open, release means movable to and from a position to engage and release the locking means and located between the opening means and pick-up position, control means selectively controlling the movement of the release means, a second switch in series with the detector switch and normally closed, and the control means opening the second
